Primary Examiner — Kevin K. Rudzinski*Assistant Examiner* — Amber J Rabie(74) *Attorney, Agent, or Firm* — Patterson Thuente Pedersen, P.A.(57) **CLAIM**

We claim the ornamental design for a cart tub, as shown and described.

DESCRIPTION

FIG. 1 is a perspective view of a cart tub showing our new design;

FIG. 2 is a top view thereof;

FIG. 3 is bottom view thereof;

FIG. 4 is a right side elevational view thereof;

FIG. 5 is a left side elevational view thereof;

FIG. 6 is a rear elevational view thereof; and,

FIG. 7 is a front elevational view thereof.

The broken lines shown in the figures define the bounds of the claimed design and form no part of the claimed design.
